UNITED STATES PATENT OFFICE.

WILLIAM HENRY JENKINS, OF TAZEWELL COURT-HOUSE, VIRGINIA.

WAGON-BODY.

SPECIFICATION forming part of Letters Patent No. 324,558, dated August 18, 1885.

Application filed April 27, 1885. (No model.)

To all whom it may concern:

Be it known that I, WILLIAM H. JENKINS, a citizen of the United States, residing at Tazewell Court-House, in the county of Tazewell 5 and State of Virginia, have invented certain new and useful Improvements in Wagon-Boxes; and I do hereby declare that the following is a full, clear, and exact description of the invention, which will enable others skilled in the art to which it appertains to make and use the same.

Figure 1 is a side view of my improved wagon-box. Fig. 2 is a bottom view of the same. Fig. 3 is a transverse sectional view 15 taken on the line $\alpha\alpha$ in Fig. 1, and Fig. 4 is a transverse sectional view taken on the line $\gamma\gamma$ in Fig. 1.

The same letters refer to the same parts in all the figures.

20 This invention relates to the construction of wagon-boxes; and it has for its object to provide a wagon-box which shall be simple in construction, durable, and which may be easily knocked down or taken apart and again put 25 together without great exercise of strength.

With these ends in view the invention consists in the improved construction and arrangement of parts, which will be hereinafter fully described, and particularly pointed out 30 in the claims.

In the drawings hereto annexed, A designates my improved wagon-box. B is the bottom or bed of the same, which is provided at or near the ends with cross pieces or braces 35 C C, and at or near the middle with additional cross-braces D D, all of which extend beyond the sides or edges of the bed, as shown. The end braces C C are provided at their outer ends with shoulders E E, and the projecting 40 or extending ends of the braces D D also have shoulders F, formed by flanges G, connecting the ends of the said braces, as shown.

H H are the sides of the wagon-bed, which are adapted to rest upon the braces C C and 45 D D, between the shoulders E and F of the said braces and the outer edges of the wagon-bed. The said sides are provided with vertical braces or standards I, the lower ends of 50 which are formed or provided with forwardly-extending hooks J, adapted to catch over the ends of the braces C and D, and thereby con-

nect the sides to the bed or bottom of the wagon-box securely against vertical displacement.

The shoulder-blocks E and the flanges G, 55 forming the shoulders F, are secured to the braces C and D, respectively, by means of vertical bolts, the lower ends of which are equipped with nuts K, which are held in position and prevented from turning by means of the hooks J upon the lower ends of the standards I, as will be clearly seen in the drawings hereto annexed.

The sides H H of the wagon-box are provided on their inner sides, near their ends, 65 with vertical cleats L L, forming guides for the end-gates M M, which are constructed with centrally-located downwardly-extending bolts N N, adapted to pass through openings O in the ends of the wagon-bed, and to be secured by means of suitable hand or thumb nuts, P P. When the latter are tightened, the end-gates are not only attached securely in their respective positions, but they serve to attach or connect the sides securely to the bottom of the wagon-bed. 70 75

From the foregoing description, taken in connection with the drawings hereto annexed, the operation and advantages of this invention will be readily understood. 80

The construction is simple and inexpensive, and it admits of the sides and end-gates being detached without difficulty or the exertion of much force.

Having thus described my invention, I claim 85 and desire to secure by Letters Patent of the United States—

1. In a wagon-box, the combination, with the bed or bottom having transverse braces or cross-pieces at or near the ends and center, 90 said braces being provided at their outer ends with perpendicular retaining shoulders, of the detachable sides set against said shoulders upon the cross-pieces and having vertical braces or standards, the lower ends of which are provided with forwardly-extending hooks, 95 substantially as and for the purpose herein set forth.

2. As an improvement in wagon-boxes, the combination of the bed or bottom having 100 transverse braces near the ends and center, said end braces being provided with the per-

pendicular retaining-shoulders at their outer ends, and the longitudinal retaining - flanges secured upon and connecting the middle braces and set against the sides of the body, 5 of the detachable sides set against said shoulders and flange having vertical standards provided with forwardly-extending hooks, substantially as and for the purpose set forth.

3. As an improvement in wagon-boxes, the 10 combination of the bed or bottom having transverse braces or cross pieces secured to its under side at and near its ends and middle, said cross-pieces being provided with the retaining shoulders and flanges, as described, 15 secured to said cross-pieces by means of vertical bolts having nuts at their lower ends, and the detachable side pieces having standards provided at their lower ends, with forwardly-extending hooks engaging the sides of said 20 nuts to prevent them from turning, substantially as and for the purpose set forth.

4. As an improvement in wagon-beds, the combination of the bed or bottom having transverse flanged or shouldered braces, the detachable sides having standards provided at 25 their lower ends with forwardly-extending hooks, and having vertical cleats on their inner sides at their front and rear ends, and the detachable end-gates having bolts adapted to extend through the wagon bed or bottom and 30 provided with suitable fastening - nuts, substantially as and for the purpose herein shown and specified.

In testimony whereof I affix my signature in presence of two witnesses.

WILLIAM HENRY JENKINS.
